[57] CLAIM

I claim the ornamental design for a playtable for children, as shown and described.

DESCRIPTION

FIG. 1 is a perspective view of a playtable for children showing my new design;

FIG. 2 is a top view thereof;

FIG. 3 is a bottom view thereof;

FIG. 4 is a right side view, the left side being identical thereto;

FIG. 5 is a front view thereof; and,

FIG. 6 is a rear view thereof.

1 Claim, 3 Drawing Sheets

FIG. 1

FIG. 3

FIG. 2

FIG. 4

FIG. 5

FIG. 6

UNITED STATES PATENT AND TRADEMARK OFFICE
CERTIFICATE OF CORRECTION

PATENT NO. : Des. 427,800

DATED : July 11, 2000

INVENTOR(S) : Dornbierer

It is certified that error appears in the above-identified patent and that said Letters Patent is hereby corrected as shown below:

On the Title Page

Under [30] Foreign Application Priority Data:

replace to read:

--Feb. 2 1998 WIPO.....012146--.

Signed and Sealed this
Tenth Day of April, 2001

Attest:

NICHOLAS P. GODICI
